UNITED STATES PATENT OFFICE.

WILLIAM UNGER AND HERMAN F. MAIER, OF BUCYRUS, OHIO.

PORTABLE WALL-SCREEN.

1,280,337.

Specification of Letters Patent.

Patented Oct. 1, 1918.

Application filed August 15, 1916. Serial No. 115,072.

To all whom it may concern:

Be it known that we, WILLIAM UNGER and HERMAN F. MAIER, both citizens of the United States, residing at Bucyrus, in the 5 county of Crawford and State of Ohio, have invented certain new and useful Improvements in Portable Wall-Screens, of which the following is a specification.

This invention relates to wall screens and 10 more particularly to such screens as are adaptable for use in Sunday school rooms, class rooms, in hospitals and in other like places where it is desired to make one room into separate or private compartments without 15 obstructing ventilation or light in an appreciable measure, and to do away with the dividing partitions or screens to permit use of the room as a single compartment.

An object of our invention is to provide 20 a screen of the nature set forth which can be constructed to be removably attached to a wall at one end, and to have the structure thereof disposed in a line from the wall to form a screen or temporary wall to ob- 25 scure the view, and which may be readily detached from the wall or other support on which it is connected so that it can be entirely removed from the operative connec- 30 tion, and can even be transported to be used at another point or in other locations.

A further object lies in so constructing the screen that it is built up of a plurality of door or separate screen sections which are connected together to be capable of fold- 35 ing, and which may be removably and interchangeably fitted so that the size of the screen can be varied.

Yet another object lies in providing means connected with adjacent sections of the 40 screen in such a manner that the various sections may be locked in varied extended positions and when brought to the folded position will be automatically locked against extension movement until the locking means is 45 manually released.

With the above and other objects in view, our invention consists in certain novel features of construction and combinations of parts which will be hereinafter set forth in 50 connection with the drawings and then more particularly pointed out in the claims.

In the drawings:

Figure 1 is a view in top plan of a screen constructed after the manner of this invention,

Fig. 2 is a view in front elevation of the screen with the parts in an extended relation.

Fig. 3 is a top plan view with the various sections of the screen folded.

Fig. 4 is a fragmentary view in elevation with parts in section to better illustrate the body of the stiffeners by which the sections of the screen are held in the desired disposition with respect to each other.

Fig. 5 is a top plan view of the structure disclosed in Fig. 4.

Fig. 6 is a view similar to Fig. 5 but showing the two adjacent screen sections folded to be right angularly disposed.

The several screen sections 1 may be constructed by having the frame works 2 thereof provided with the central filler 3 which might be one of the variously so called wall boards, a fabric, or other suitable material, or for that matter the screen sections 1 might be constructed to be solid. These various sections 1 are made rectangular in form and are hinged together at their edges by the hinges 4, which are preferably of the loose butt type so that the various sections may be removably and interchangeably fitted in place in their hinged mountings. The members 1 are connected together in the manner shown in Fig. 2 so that a plurality of the sections when connected together will form a screen of some length, and a mounting strip 5 is connected upon a wall, post, or other suitable support and has one of the end sections 1 hinged thereto to be capable of swinging movement.

It is preferable that the several sections 1 have the wheels or casters 6 at the corners thereof and thus the entire structure will be supported on the floor or other structure adjacent to which it is extended, and by providing the handle or pull 7 on the end portion, this end section may be moved to give the proper extension to the remaining hinged sections.

Each of the sections 1 on its top edge adjacent to one side has a groove 8 cut or otherwise formed thereto, these grooves being extended for some distance along the top edge and lying parallel with the side faces of the members 1.

Stiffener members 9 which are made preferably of metal rods having some resiliency are at their ends bent to extend substantially at right angles to the line of extent of the

main body portion and the right angularly bent end 10 has a bearing eye 11 formed thereon. The remaining end 12 of the rod 9 as bent at right angles to the body portion is given another right angular bend so that it lies in right angular disposition to both the portion 12 and the portion 9 at its extreme end as at 13. A pin 14, or other suitable pivot means is mounted through the bearing 11 and is secured in the top edge of one of the sections 1 so that the extreme opposite end 13 will be received in the groove 8 of the next adjacent member 1. By this arrangement of the parts, the end 13 of the stiffening rod has movement in the groove 8 and the natural resiliency of the rod from which this member 9 is constructed tends to hold the lower end of the rod in engagement against the bottom of the groove, for which purpose it is preferable that this end be provided with the ball 14, as better shown in Fig. 4. The socket openings 15 are sunk into the material of the members 1 at the bottom of the grooves 8 and socket liners 16 are mounted in these sockets to prevent wear. As the members 1 are swung around their hinged mountings, the end 14 will travel on the bottom of the groove 8 and as the socket openings are engaged the rods will spring into these openings which will cause the stiffeners to hold the adjacent screen sections against further swinging movement in either direction.

In the use of the device, the mounting strip 5 will be secured on a wall, post, a piece of furniture, or any other desired point and the several sections or members to make up the completed screen are hingedly connected together and are connected with the mounting strip 5 through the hinges as above set forth. In this mounting of the sections 1, the casters 6 will rest upon the floor adjacent to the mounting strip 5 when the parts are in the folded relation as shown in Fig. 3 and as the ends 13 of the stiffener members 9 are engaged in certain of the sockets 15 formed in the bottom of the grooves 8, the several sections will be held in this folded relation until the stiffener members 9 are manually released from the securing positions when the sections 1 may be extended so that they will be disposed in any angular relation with respect to each other up through the full extended relation as shown in Fig. 1 where the sections are in alinement and then when the parts have been brought to this relation the ends 13 of the stiffener members will engage in still other of the sockets and will consequently hold the sections 1 in the full extended relation. It will be understood that any number of socket openings 15 might be provided in each of the members and thus any number of angular settings of the screen sections might be accomplished, however, under ordinary cir-

cumstances where the casters 6 are resting on the floor and the ends 13 bear against the bottom of the grooves 8, the screen sections will be held against casual displacement from any angular setting in which they may be arranged, even though the ends 13 may not be engaged in the socket openings.

From the foregoing it will be seen that we have constructed a wall screen structure, the individual members of which may be made in any height or width to suit the conditions which are to be met, and they may also be constructed in various styles and of various materials to blend with the surroundings in which they are to be used, and that the screen is sanitary, self-supporting, readily portable, and at the same time presents the structure in such form that screens of various lengths may be constructed by taking a predetermined number of sections and connecting the same together by the insertion of the hinged butts and also the structure may be extended in various angular dispositions to form entirely inclosed separate compartments, to form partitions, or in any other desired configuration.

While we have herein shown and described only one specific form of the structure, it will be understood that various mechanisms might be employed in the place of the stiffener members, that the individual sections might be constructed in other forms than herein shown, and that a number of modifications and changes might be resorted to in the form and arrangement of the several parts without departing from the spirit and scope of our invention, and hence we do not wish to be limited to the exact disclosure but only to such points as may be set forth in the claims.

We claim:

1. A folding wall screen comprising a plurality of sections hingedly connected together, said parts being so arranged that the various sections may be extended to be disposed in alinement or may be disposed in various angular dispositions, grooves provided in each of said sections to form guideways, sockets formed at various points in conjunction with the grooves, stiffening members pivotally mounted on each of said sections and provided with angularly disposed ends to be received in the grooves and slide therein as the sections are swung about their hinged mountings, the stiffening members having sufficient resiliency so that as the angularly disposed ends come into registry with the sockets this end will spring thereinto and will hold the sections in the desired adjusted positions.

2. A folding wall screen comprising a plurality of sections, hingedly connected together, stiffening members pivotally secured to said sections and capable of having horizontal swinging movement, said stiffen-

ing members formed of spring metal, each section provided with a plurality of adjusting sockets arranged therein, and each stiffening member provided with a depending knob adapted to fit within one of said sockets, means for detachably and automatically locking said sections in various adjusted positions with respect to each other.

In testimony whereof we affix our signatures in presence of two witnesses.
